UNITED STATES PATENT OFFICE.

ENOCH OHNSTRAND, OF MOHAWK, NEW YORK, ASSIGNOR TO LIBRARY BUREAU, OF CAMBRIDGE, MASSACHUSETTS, A CORPORATION OF NEW JERSEY.

FIRE-RESISTANT CABINET.

Application filed January 28, 1922. Serial No. 532,443.

To all whom it may concern:

Be it known that I, ENOCH OHNSTRAND, a citizen of the United States, and resident of Mohawk, in the county of Herkimer and 5 State of New York, have invented new and useful Improvements in Fire-Resistant Cabinets, of which the following is a specification.

This invention relates in general to improvements in fire-resistant cabinets such as vaults, safes, filing cases, etc., and in particular to the provision for maintaining a tight joint between the walls of the cabinet and the door or doors therefor.

15 When a cabinet of this character is subjected to heat, as in a fire, it frequently happens that the sides of the cabinet bulge outwardly as a result of expansion and contraction and produce a crack or opening between the door and the adjacent sides of the cabinet up to three quarters of an inch in width, or more depending upon the size of the door and the thickness of the cabinet walls, the crack or opening frequently developing to the greatest extent in the cooling 25 of the cabinet following the intense heat. The door hinges are unable to resist such a strain and are usually so deformed that the contents of the cabinet are exposed to the fire 30 and water and after the fire it is difficult to open the door. In addition a permanent "set" is produced in the walls of the cabinet so that the latter is rendered unfit for further service without extensive and costly re- 35 pairs.

Objects of the invention are to prevent the development of cracks or openings between the walls of fire-resistant cabinets and their doors, better to safeguard the contents of 40 such cabinets during and following a fire, to protect the hinges of such cabinets against shearing strains and deformation due to bulging of the cabinet walls, to prevent permanent deformation of the walls adjacent 45 the doors of such cabinets, and in general to improve the construction of such cabinets.

The invention comprises providing the swinging door and casing of a fire-resistant cabinet with overlapping portions and further providing a projection or lug upon one of said portions received in an opening or recess in the other portion when the door is closed. The portion of the door which overlaps the casing may be an integral part of 55 the door, or a member or plate fast thereon,

such as one part of the hinge upon which the door pivots. The lug or projection is preferably substantially tangential to the arc of swing of the door or substantially perpendicular to the plane of the door when 60 closed. The opening in which the lug or projection is received may extend entirely through its portion of the door or casing. When the part of the hinge fast or integral with the door is made use of as the aforesaid 65 overlapping portion, the hinge is pivoted to the casing at a point spaced from the edge of the opening normally closed by the door.

In order to illustrate the invention one concrete embodiment thereof is shown in the 70 accompanying drawings, in which:

Fig. 1 is a perspective view of a heat resisting cabinet showing the features of the invention; and

Fig. 2 is an enlarged section on the line 75 2-2 of Fig. 1.

The embodiment of the invention shown for the purpose of illustration comprises a fire-resistant cabinet of usual appearance having a framework of angle iron 3 enclosing the edges of the cabinet, the parts making up the framework being suitably united at the corners. The walls of the cabinet are of the usual construction comprising outer and inner metallic casings 4 and 5 respectively, the intervening space being filled with 80 a suitable heat insulating material 6. The cabinet is provided with double doors 7 and 8, the usual bolt operating handles 9, and combination lock 10. 85

Doors 7 and 8 are pivoted to the cabinet by means of hinges comprising parts 11 integral with or attached to the doors in any suitable manner as by welding or riveting and the parts 12 fast upon the cabinet itself. 90 The pivots 13 of the hinges are spaced from the edges of the door opening of the cabinet and in the embodiment shown are at the corners of the structure. Adjacent portions of the cabinet and the doors are provided with 100 reinforcing plates or strips 14 and 15 respectively.

According to the present invention the hinge portions 16 of the doors overlap the adjacent portions of the cabinet. These 105 overlapping hinge portions are provided with recesses or openings 17 receiving, when the door is closed, a projection or lug 18 fast in the cabinet and disposed substantially tangential to the arc of swing of the 110

door or perpendicular to the plane defined by the doors in their closed position. This lug has an axial reduced portion 19 forming a shoulder 20 which rests upon one face of angle member 3, the lug being tightly clamped in place by means of a nut 21 threaded on its exposed inner end and contacting reinforcing strip 14.

Sufficient clearance is provided between 10 openings 17 and lugs 18 to permit the hinges to swing freely in opening and closing the doors but the clearance is not great enough to permit substantial separation of the doors from the casing during the expansion or 15 contraction of the structure in or after a fire.

When a cabinet of this type is subjected to intense heat, the top and bottom portions thereof are substantially undeformed by 20 expansion due to the rigid frame of relatively short angle irons 3. The long vertical portions, however, adjacent the doors tend to warp or bulge outwardly and separate from the doors, this warping frequently 25 occurring in the cooling stage following a fire. The short lugs 18 firmly anchored in the long frame members 3 and engaged by the overlapping portions 16 of the hinge members, which are integral or fast to the 30 door, effectively withstand the outward movement of frame members 3, thus protecting the cabinet from distortion and the hinge pivots 13 from injury.

I claim:

35 1. A fire-resistant cabinet comprising a casing having an opening, a swinging door for closing said opening, portions of the casing and door overlapping when the door is closed, and complementary means on said 40 overlapping portions providing interengaging surfaces substantially perpendicular to the plane of the outer face of the door when closed thereby to restrain bulging of the walls of the safe and the spreading of the 45 cracks between the door and the door casing when the cabinet is subjected to intense heat.

50 2. A fire-resistant cabinet comprising a casing having an opening therein, a swinging door for closing said opening, a portion of said door overlapping a portion of said casing when the door is closed, one of said portions having a pin whose inner side is substantially tangential to the arc of swing

of the door, and the other of said portions 55 having a socket adapted to receive said pin when the door is closed.

3. A fire-resistant cabinet comprising a casing having an opening therein, a swinging door for closing said opening, a portion 60 fast to said door overlapping a fixed portion of said casing when the door is closed, one of said portions having a pin whose inner side is substantially perpendicular to the plane of the door when closed, and the other 65 of said portions having a socket adapted to receive said pin when the door is closed.

4. A fire-resistant cabinet comprising a casing having an opening therein, a door to close said opening, and a hinge having one 70 part fast on said door and the other part fast to said casing, said parts being pivoted together at a point spaced from the edge of said opening whereby a portion of said first named part of said hinge overlaps a portion 75 of the casing, said casing and said overlapping portion of said hinge having an interfitting lug and socket engagement when the door is closed to restrain the crack between the door and casing from spreading. 80

5. A fire-resistant cabinet comprising a casing having an opening therein, a door to close said opening, a hinge having one part fast on said door and the other part fast 85 to said casing, said parts being pivoted together at a point spaced from the edge of said first named part of said opening whereby a portion of said hinge overlaps a portion 90 of the casing, a projection on said casing, and a recess in said overlapping portion of said hinge arranged to receive said projection when said door is closed.

6. In a fire-resistant cabinet having double doors and hinges having parts fast on said cabinet and other parts fast on the doors, said parts being pivoted together at points spaced from the edges of the opening closed by the doors whereby the parts of said hinges attached to the doors overlap portions of the sides of the cabinet, means for 100 preventing outward bulging of the sides of the cabinet comprising openings in said last named parts of the hinges cooperating with lugs on the overlapped portions of the cabinet when the doors are closed. 105

Signed by me at Mohawk, N. Y., this 24th day of January, 1922.

ENOCH OHNSTRAND.
